Patented August 4, 1903.

UNITED STATES PATENT OFFICE.

GEORGE D. CHISHOLM, OF CHICAGO, ILLINOIS.

DESIGN FOR A STAND.

SPECIFICATION forming part of Design No. 36,481, dated August 4, 1903.

Application filed June 18, 1903. Serial No. 162,143. Term of patent 7 years.

To all whom it may concern:

Be it known that I, GEORGE D. CHISHOLM, a citizen of the United States, residing at Chicago, in the county of Cook and State of Illinois, have invented a new, original, and ornamental Design for Stands, of which the following is a specification, reference being had to the accompanying drawing, forming part thereof.

The figure is a perspective view illustrating my new design.

What I claim as new is—

The ornamental design for a stand, herein shown.

GEORGE D. CHISHOLM.
